UNITED STATES PATENT OFFICE

2,119,186

HULLER RIB

John A. Streun, Sherman, Tex., assignor to Hardwicke-Etter Company, Sherman, Tex., a corporation of Texas

Application January 27, 1937, Serial No. 122,666

11 Claims. (Cl. 19—62)

The present invention relates to improvements in the construction and operation of cotton huller gins and more especially to simple, efficient and economical means for preventing the clogging or collecting of cotton at the top of the huller ribs during the operation of the gin, and means for feeding the cotton into the roll box to be ginned without breaking or damaging the same.

It has been found that in cotton gins of the solid rib type as formerly used, the staple cotton has a tendency to clog in the spaces between the solid ribs and the saws at the top of the huller ribs, due to the fact that no means were provided either to remove or to permit the escape of the cotton collected at these points. Further, because the staple cotton is more or less stringy, the locks also have a tendency to be caught by the saws which causes the ends of the locks to be pulled through the ribs so that the centers of the stretched out locks are wrapped around the ribs and start what is called "clogging up the top of the huller ribs" at points immediately above the saws. This congestion of the cotton necessitates the operator stopping the gin to remove the lodged cotton and also is liable to set the cotton on fire due to the frictional engagement of the saws with the bunched cotton. A further disadvantage found in the solid rib huller gin is that when the cotton starts to clog the ribs, the ends of the locks of cotton protrude inwardly and obstruct the passage between the huller ribs and the ginning ribs with the result that the seed from the roll box cannot be discharged therefrom. This congestion causes the roll in the roll box to be tightened, which damages the sample and grade of the lint. A further disadvantage found to exist in the closed rib type and in types in which no provision is made to prevent the clogging or removal of the cotton from the huller ribs, is that when the ribs clog, the capacity of the gin is reduced since the saws will continue to wedge or force more cotton into the clogged places at the top of the ribs, thus damaging the sample or grade of the cotton by reason of the preginning at the clogged points. This clogging also produces a grade of lint full of naps and kinks attributable to the cotton being dragged through the obstructed openings between the ribs.

An important feature of the present invention is to overcome these objections by providing the huller gin with split ribs having upper and lower huller rib sections separated by a transversely disposed gap adjacent the saw teeth or the saw point, and associating with the upper section of the ribs, revoluble means positioned in close proximity to

but spaced from the ribs and the gap, to impart a wiping action to the locks of cotton collected on the upper section so as to move them toward the gap, said revoluble means also act to strip the saws and move back any hulls that may approach the gap, to prevent the hulls from entering the spaces between the ribs and the gap.

A further object consists in associating with the gin saws and the roll box, an upper plate having spaced partially closed downwardly and outwardly extending ribs, and a lower plate having upwardly projecting ribs registering with adjacent ribs on the upper plate but spaced therefrom to provide a gap or opening between the opposed ends of the ribs on the plates. The spaces between the ribs of the upper plate instead of being completely closed and of the same width throughout their length, are provided with ribs or walls which extend from the closed ends of the ribs toward their open ends and terminate short of the open ends to provide a through opening between adjacent ribs. The partially closed portions or webs between the ribs of the upper plate extend across the top of the ribs and are preferably shaped to provide a recess or groove between adjacent ribs which is enclosed at its upper end by a curved or concave tapering inner wall that decreases in area toward the closed ends of the ribs where it merges into the outer surface of the upper plate. The webs serve to prevent seed from escaping from the roll box into the huller chamber, and also prevent cotton from straddling the ribs of the upper plate or projecting into the roll box. Further, the partial closing of the spaces between the ribs of the upper plate render it unnecessary to provide a picker roll having fingers or spikes extending between the ribs to keep them clear, such as is shown in my copending application now Patent No. 2,104,889, dated January 11, 1938.

Another object consists in associating with a split huller rib and adjacent the gap between the plates, a revoluble member having a series of independently removable sleeves or tubular members, each of which is provided with diametrically opposed segmental vanes or blades arranged adjustably to be moved into close proximity to the ribs and gap so that when the blades are rotated at a high rate of speed, they provide a wiping action for the purpose of stripping the ribs of the upper plate of any cotton collected thereon and also prevent hulls or particles of large foreign matter from passing between the ribs and into the roll box.

A further object consists in associating with

the web which partially close the ribs of the upper huller plate, movable seed fingers arranged directly above and in substantial registration with adjacent ribs of the upper plate, for the purpose of adjusting the density of the roll in the roll box by raising or lowering the roll relative to the saw teeth in order to control the rate of ginning and the escape of the seed from the roll box without danger of the seed falling into the huller 10 chamber.

Other objects and advantages of the invention will become apparent from the following description when taken in conjunction with the accompanying claims and drawings.

15 Referring to the drawings, in which there is shown a preferred embodiment of the invention,

Figure 1 is a vertical sectional view of a cotton gin having the huller ribs and their associated parts constructed in accordance with my invention;

20 Figure 2 is a sectional view taken substantially along the line 2—2 of Figure 1;

Figure 3 is a sectional view taken substantially along the line 3—3 of Figure 2;

25 Figure 4 is a sectional view of the upper huller plate or section taken substantially along the line 4—4 of Figure 1;

Figure 5 is a detailed perspective view of one of the upper plates of the huller ribs;

30 Figure 6 is a perspective view of the blade or vane type revoluble members that are associated with the split huller ribs.

Referring to the drawings in which like numerals indicate like parts in the several views, 35 10 designates a gin frame to which is pivotally connected the gin breast 11 as at 12. Fastened to a revoluble shaft 13 is a saw cylinder 14 to which is secured a series of axially disposed spaced gin saws 15 that may be operated in the 40 usual manner, by suitable driving means, not shown.

The gin breast 11 preferably comprises a rear member 16 (Fig. 1) having an upper roll box section 17 and a lower section 18. Associated 45 with the rear member 16 is a huller breast or forward member 19 pivoted as at 20 to the gin breast, and provided with a coacting upper roll box section 21 and a lower section 22. The upper sections 17 and 21 constitute the roll box 23 which is of suitable shape to accommodate the 50 change in pressure on the roll to insure the roll turning freely in the roll box during the ginning operation. A series of curved gin ribs 24 are suitably secured at their ends to the rear section 16.

The huller ribs of the gin instead of being closed are split or interrupted, and are preferably composed of a series of lower plates 25 with which is associated a huller rib rail 26 having 55 elongated slots 27 through which screws 28 extend so as to be threaded into aligned openings in a transversely disposed bar 29 on the lower section 22, for the purpose of securing the plates 25 to the gin. The elongated slots 27 permit 60 the plates 25 to be adjusted vertically and these plates may be retained in their adjusted position by set screws 30 which bear against the outer face of the rib rail 26. Projecting upwardly from each of the plates 25 are a series of 65 huller ribs 31 between which extend the gin saws 15 in the manner as shown in Figure 1, when the parts are in their operative positions.

Associated with each of the lower plates 25 is an upper plate 32 which may be secured to the front of the huller breast adjacent the bot-

tom of the roll box 23 by the screws 32'. The plates 32 have extending downwardly and outwardly therefrom, spaced thin huller ribs 33 which are wider at their lower ends than at their upper ends. These ribs register with the ribs 31 on the lower plate, but are spaced therefrom to provide a transversely disposed gap 34 that extends the length of the huller breasts and projects outside the teeth 35 of the gin saws. The ribs 33 on the upper plates 32 are shorter and 10 thinner than the ribs 31 on the lower plate and instead of being open throughout their length, are partially closed by a web or wall 36 extending from the top of these ribs to close the space between adjacent ribs, so as to provide the recesses 15 or depressions 37 which extend lengthwise between the ribs 33 and the web 36. While the plates 25 and 32 have been shown formed of a series of separately longitudinally disposed sections, carrying a plurality of upper and lower 20 ribs and secured to the gin breast, it will be understood that this construction may be varied mechanically. For example, the ribs 31 and the ribs 33 could, if desired, be individually formed, together with their supporting plates, and secured singly in operative relation to one another, or the plates 25 and the plates 32 may be constructed in one piece with the ribs projecting therefrom.

The web 36 extends from the upper closed 30 ends of the ribs 33 toward their lower open or free ends and terminates short of these ends to provide through openings 38 between adjacent ribs (Figure 5). The partially closed portions or webs 36 between the ribs 33 are preferably shaped 35 to constitute curved or concaved inner walls 39 between the ribs. These walls extend upwardly and decrease in area towards the closed ends of the ribs where they merge into the outer surface of the plate 32. The lower end portions of the webs 36 between each of the ribs 33 terminates in a curved or tapered edge 40 spaced from the gap 34, while the lower ends of the ribs 33 preferably are formed with rounded corners or edges 41.

A revoluble shaft 42 extends transversely through the sides of the gin and is supported by the hangers 43 pivotally connected to the sides of the gin breast as at 44. Each of the hangers 43 has spaced arcuate slots 45 and 46 through 50 which extend the threaded bolts 47 that are received in complementary threaded openings formed in the sides of the gin breast to secure the shaft 32 in its desired adjusted position. A series of longitudinally disposed sleeves or tubular members 48 are fastened to the shaft in any suitable manner, such as by the set screws 49 so as to be independently removable therefrom. Extending outwardly from each of the sleeves are a pair of diametrically opposed blades or 55 vanes 50 which may be curved rearwardly so as to be of segmental shape. The ribs on each sleeve 48 are preferably disposed at substantially right angles to the ribs on the adjacent sleeves so that alternate ribs are in substantially the 60 same vertical or horizontal planes (Figure 6).

The front portion 19 of the gin breast is provided with a huller breast chamber 51 spaced in front of the section 21 to receive the cotton and conduct the same to the picker roll 52. A 70 deflecting plate 53 supported at its lower end by a bracket 54 secured to the inner wall of the gin breast, acts to direct the cotton toward the gin saws 15. Below the picker roll 52 is a trough 55 in which is revolvably mounted a screw con- 75

veyor 56 for removing, from the gin, trash, dirt and other foreign matter which fall from the cotton in the huller chamber. The cotton as it passes from the deflector plate 53 is conducted by the picker roll 52 to the gin saws 15 which catch the lobes of seed cotton and carry them up between the split huller ribs so that the stringy locks are caught by the saws and conducted into the roll box.

10 The cotton carried by the saws through the roll box is removed from the gin in any suitable manner such as by a blast of air delivered to the nozzle 57 toward the outlet or discharge flue 58. An adjustable mote board 59 above the nozzle 57 acts to deflect the motes downwardly toward the conveyor 60 for removing the same from the gin.

15 A revolvable shaft 61 extends transversely of the gin breast and above the upper plates 32, and is provided with a series of radial, spaced seed fingers 62 (Figure 2) which are located directly over the web 36 and the ribs 33 so that a finger is positioned between each of the gin saws. An operating handle 63 fastened outside 20 of the gin to the shaft 61 (Figure 3) actuates the fingers and may be retained in a predetermined fixed position by a rack member 64 secured by the screws 65 to the gin breast. The lower portion of the roll box 23 may have a depending flexible skirt 66 which extends a sufficient distance to yieldably engage the seed fingers 33 so as to be movable therewith when the shaft 61 is actuated. Upon the operation of the handle 63, the fingers 62 may be raised or lowered to adjust the density of the roll in the roll box 23. By raising the roll from the saw teeth, the rate of ginning and the escape of the seed through the discharge passage 67 formed between the ginning ribs and the hulling ribs may be 25 retarded.

20 The shaft 42 which carries the segmental blades 50 is arranged to be operatively connected to the driving mechanism which operates the gin in any suitable manner, and may have fastened thereto a pulley wheel 68 which is connected to the picker roll 52 by a belt so as to revolve at a relatively high rate of speed when the gin is in operation.

25 The section 21 of the roll box 23 preferably is hinged at its upper end as at 69 to the member 19 to permit convenient access to the roll box, and has its lower end coacting with a relatively fixed portion or member 70 to constitute the front of the roll box. The member 70 constitutes an upper huller rib rail to which the plates 32 may be secured by the screws 32'.

30 In operation it will be seen that as the cotton is fed to the huller chamber 51, it is deflected by the plate 53 toward the picker roll 52 which rotates in a counter-clockwise direction so as to conduct the cotton to the gin saws 15. The saws catch the seed cotton and convey it up between the huller ribs in such a manner that if any stringy locks are caught by the saws, they will be passed into the roll box 23 through the gap 34 and will not have a tendency to wind around the ribs or interfere with the efficient operation of the gin saws.

35 Should any of the cotton be carried past the gap 34 and collect on the ribs 33 of the upper plate 32, the wiping action imparted by the blades 50 which rotate in a counter-clockwise direction and at a high rate of speed, will serve to move or knock the locks downwardly toward the gap 34 so as to clear the plates 32. The

blades will also strip any hulls back to prevent them from entering between the ribs or the gap into the roll box. The hangers 43 carrying the shaft 42 are, of course, previously adjusted by the operator, so that the blades 50 are positioned in proper close proximity to the ribs 33 and the gap 34 to insure the removal of the cotton from the plate 32 during the operation of the gin.

40 The web 36 is so shaped and positioned as not only to prevent the seed from escaping from the roll box 23 into the hulling chamber 51, but also precludes the cotton from straddling the ends of the ribs 33. The web also eliminates the possibility of the lint on the huller ribs from extending into the roll box between the ribs 33. As 45 the end portions 40 of the web 36 terminate short of the ends of the ribs 33, they provide the openings 38 which allow the seed to fall undamaged into the discharge passage 67. Further, since the ends 41 of the thin ribs 33 are 50 rounded, they will prevent the crushing of the seed during the ginning operation and will permit the seed to fall or slip over into the openings 38 without being damaged.

55 By reason of the adjustability of the shaft 42, the blades 50 may be moved toward or away from the huller ribs depending upon the grade or type of cotton being ginned. Moreover, the adjustable connection of the lower plates 25 to the bar 29 by the screws 26 permits the space or gap 34 60 between the opposed inner ends of the split huller ribs to be varied in accordance with the quality of the cotton being ginned. The set screws 30 which engage the rail 26 insure each plate 25 being firmly secured in the desired position relative to its complementary upper plate 32 in order to maintain the gap 34 uniform and constant throughout the length of the gin breast. Arcuate slots or openings 11 (Fig. 3) in the sides of the gin breast permit the shaft 42 to be moved so 65 that the blades 50 may be secured in their proper adjusted positions relative to the ribs 33 and the gap 34.

70 As the web 36 partially closes the top or upper sides of the huller ribs 33 and is positioned directly beneath the seed fingers 62, it will not only preclude the seed from falling into the huller chamber 51, but will also act to prevent the cotton from straddling the ribs 33 and extending into the roll box between the ribs. Further, when the fingers 62 are raised by the actuation of the handle 63, the roll in the roll box may be tightened by lifting the cotton off the saws and exposing less teeth to act on the cotton in the roll without danger of the cotton becoming 75 congested at the top of the huller ribs.

75 As shown, the ribs 33 are formed integral with the plate 32 and extend downwardly and outwardly from one side thereof and have their inner edges 72 slightly curved to facilitate the removal of the cotton therefrom. The web 36 may be considered as extending from the opposite side of the plate 32 and constitutes a portion of the plate which overlaps the spaces between the ribs and terminates short of the free ends 80 of the ribs to close the same and provide the recesses 37.

85 It will be seen that by reason of the novel association of the blades 50 with the partially closed huller ribs 33 and the gap 34, that efficient 90 and positive means are provided to prevent the cotton from wrapping or looping around the ribs and collecting at the top thereof, and for imparting a wiping and smoothing action to the cotton collected on the ribs 33 in order to move 95

the same toward the gap 34 where the cotton is caught by the teeth of the saws 15 and carried through the roll box so as to be discharged from the gin through the flue 58, without being broken or damaged.

While the revoluble means for conducting the cotton through the gap shown in my Patent No. 2,104,889, works satisfactorily when the cotton is fed at a regulated speed, it is open to the 10 objection that if the cotton is overfed to the hulling chamber, the seed and cotton are damaged during the ginning operation. Thus, if the operator in starting the gin allows a large batch to accumulate and then dumps the entire mass 15 into the hulling chamber, the quantity of the cotton is such that the saws are unable to pitch a batch of the cotton up at one time to the gap. The teeth on the auxiliary roller during their counter-clockwise rotation will catch some of the 20 cotton in the hulling chamber and force the same over the top of the teeth and down between the teeth of the roller and the upper rib plates, thus wedging the cotton against the ribs, which seriously damages the staple by the thrashing 25 effect produced. This lowers the grade of the cotton which is the first to go into the bale and which is on the side the sample is taken from. Consequently, the farmer is deprived of the best and only real sample of the bale, which means 30 he must take a lower price for his cotton due to its damaged condition.

The damaging of the cotton in this manner is avoided in the present invention, since if the gin is overfed, the recesses 37 between the thin 35 huller ribs and the web 36 constitute means in the form of grooves for receiving the seed and the cotton that clings to the seed and pushes the same between the ribs 33 into the recesses 37 without injury to either the seed or the fiber. 40 In other words, if the operator allows the cotton to accumulate in the seed chute and on starting the gin, dumps the entire mass into the hulling chamber 51 so that some of the unginned cotton is caught by the blades 50 and carried downwardly past the ribs 33, the rearward curvature 45 of the blades will coat with the complementary curved portions of the ribs 33 so as not to produce a tearing effect on the cotton fibers as would be the case if a straight vaned rib were used. Moreover, as the blades 50 brush the cotton downwardly past the ribs 33, the seed clinging to the 50 cotton is pushed in between the ribs into the grooves 37 without injury to either the seed or the fiber. If the huller ribs were solid or if the grooves 37 were not provided, the cotton would be wedged against the ribs, which would not only damage the lint due to the mass passing over the ribs but would also crush the seeds in the cotton and destroy the same. Further, the 55 husks of the seed would remain in the lint and be conducted to the roll box to form a part of the sample which would lower the grade and value of the lint.

The saws 15 are arranged to run close to the 60 blades 50 so that when the cotton is fed in a steady stream and at the proper rate of feed, the cotton will not be carried by the blades 50 past the ribs 33, due to the fact that the backward curve of these blades will not allow any 65 loose strands to ride thereon or back up the cotton locks as would be the case if straight teeth or ribs were used. Consequently, the cotton will be prevented from collecting on the upper rib sections.

It will be appreciated that the saws rotate at

a very high speed so that the centrifugal force developed has a tendency to throw the cotton loose from the saws. If the cotton is caught by more than one saw, the loop catches on the end of the upper ribs 33 and is immediately brushed downwardly to the gap 34 by the blades 50 and then is carried by the saws through the gap into the roll box 23. If the centrifugal force fails to throw the cotton up to the gap and the cotton tries to loop over the ends of the lower ribs 31, 10 the oncoming cotton which is held by the saw teeth acts to drive these loops up over the rib ends and through the gap. Thus, the saws always keep the ends of the lower ribs clear of the loops, while the auxiliary roller or blades 50 move 15 any cotton that might collect on the upper short ribs downwardly toward the gap.

The blades 50 also tend to reduce the bulk of the cotton so that it will pass through the gap without wedging, and if any of the lint should 20 work its way over the top of the shaft 42, the same is wiped back to the gap without injury either to the cotton or the seed.

Thus, it will be seen that by virtue of the novel association of the webbed ribs 33 and the blades 25 50 with the other parts of this gin, means are provided for eliminating seed wastage and for preventing the crushing of the seed and the congestion of the cotton against the saw teeth.

It is to be understood that the form of the invention shown is merely illustrative of a preferred embodiment, and that such changes may be made as fall within the purview of one skilled in the art without departing from the spirit of the invention and the scope of the appended claims. 30 35

I claim:—

1. A cotton gin of the class described including gin saws, huller ribs in cooperative relation to the saws, said ribs being interrupted to provide an upper section and a lower section separated 40 by a transversely disposed gap, said upper section having a web connecting the adjacent ribs and terminating short of the free ends thereof to provide openings between the ribs adjacent the gap, a shaft revolubly mounted in the gin, and a series of axially disposed sleeves independently fastened to the shaft, each of said sleeves having opposed segmental blades positioned substantially at right angles to the adjacent blades, said blades arranged to be rotated in close proximity 50 to the ribs whereby to move the cotton collected on the upper section toward the gap and the gin saws during the operation of the gin.

2. A cotton gin of the class described including gin saws, spaced huller ribs in cooperative relation to the saws, said ribs being interrupted to provide an upper section and a lower section separated by a transversely disposed gap extending outside the saws, said upper section having the tops of the ribs closed, the inner walls between the 55 ribs of the upper section being curved and terminating short of the lower free ends of the ribs to provide openings adjacent the gap, and revoluble means disposed relative to the upper section and the gap to impart a wiping action to the 60 cotton collected on the upper section to move the same toward the gap, the spaces between the ribs of the upper section coating with their closed tops to form recesses for receiving the cotton seed and prevent the latter from being damaged 65 by the revoluble means during the operation of the gin.

3. A cotton gin of the class described including gin saws, hulling ribs in cooperative relation to the saws, said ribs being interrupted to pro- 70 75

vide an upper section and a lower section separated by a transversely disposed gap, said upper section having webs connecting the top of the ribs and terminating short of the free ends thereof to provide opening between the ribs adjacent the gap, a revolute shaft mounted in the gin, and a series of axially disposed sleeves fastened to said shaft, each of said sleeves having diametrically opposed segmental blades disposed substantially at right angles to the blades of the adjacent sleeves, said blades being positioned in close proximity to the ribs of the upper section whereby to move cotton collected on the upper section toward the gap and the gin saws.

15. 4. In a cotton gin of the class described, a roll box, gin saws associated with the roll box for conducting the cotton thereto, an upper plate secured to the roll box adjacent the saws and provided with downwardly extending spaced ribs, a lower plate secured to the gin and having upwardly projecting spaced ribs registering with adjacent ribs on the upper plate, the aligned ribs on said plates being spaced from one another adjacent the teeth of the saws to provide a gap 25 which extends beyond the saws, said upper plate having the top surfaces of the ribs closed by a web except at the ends adjacent the gap, the inner wall of the web between the ribs being concaved and converging toward the gap, and revolute blades in close proximity to the ribs of the upper plate for conducting the cotton collected thereon to the gap and the gin saws during the operation of the gin, the spaces between the ribs of the upper section coacting with the web to 35 form grooves for receiving the seed and prevent the latter from being damaged by the blades.

5. In a cotton gin of the class described, a roll box, gin saws associated with the roll box for conducting the cotton thereto, an upper plate secured to the roll box adjacent the saws and provided with depending spaced ribs, a lower plate secured to the gin and having upwardly extending spaced ribs registering with adjacent ribs on the upper plate, the aligned ribs on said plates being spaced from one another adjacent the peripheries of the saws to provide a gap which extends beyond the saws, the ribs of the upper plate being provided with rounded corners and connected by web portions terminating short of the free ends of the ribs to provide open spaces between the ribs adjacent the gap, a series of seed fingers pivotally mounted in the front of the roll box, said fingers being disposed above and in vertical alignment with adjacent ribs on the upper plate, and a revolute member having a plurality of opposed and alternately disposed blades positioned in close proximity to but out of engagement with the spaces between the ribs in the upper plate whereby to move cotton collected on the ribs of the upper plate toward the gap and the gin saws.

6. In a cotton gin of the class described, a roll box, gin saws associated with the roll box for conducting the cotton thereto, an upper plate secured to the roll box adjacent the saws and provided with depending spaced ribs, a lower plate secured to the gin and having upwardly extending spaced ribs registering with adjacent ribs on the upper plate, the aligned ribs on said plates being spaced from one another adjacent the peripheries of the saws to provide a gap, the ribs of the upper plate being provided with rounded corners and connected by web portions terminating short of the free ends of the ribs to provide open spaces between the ribs adjacent the gap,

revolute members having axially disposed blades extending radially therefrom, the adjacent blades being positioned substantially at right angles to one another and arranged to move into close proximity to the ribs to impart a wiping action to the cotton collected on the upper blade so as to move the same toward the gap and the gin saws, and means for adjusting the blades relative to the ribs.

7. A cotton gin of the class described, a roll box, gin saws associated with the roll box for conducting the cotton thereto, an upper plate secured to the roll box adjacent the saws and provided with depending spaced ribs, a lower plate secured to the gin and having upwardly extending spaced ribs registering with adjacent ribs on the upper plate, the aligned ribs on said plates being spaced from one another adjacent the peripheries of the saws to provide a gap, the ribs of the upper plate having rounded corners and closed at their tops by webs terminating short of the free ends of the ribs to provide open spaces between the ribs, a series of seed fingers pivotally mounted in the roll box, said fingers being disposed above and in alignment with adjacent ribs on the upper plate, a shaft on the roll box adjacent the longitudinally disposed saws, and a series of segmental blades extending outwardly from the shaft, said blades being alternately disposed at right angles to adjacent blades and in close proximity to the ribs of the upper plate whereby to move the cotton collected on the upper plate toward the gap and the gin saws.

8. In a cotton gin of the class described, a roll box, gin saws associated with the roll box for conducting the cotton thereto, an upper plate secured to the roll box adjacent the saws and provided with downwardly extending spaced ribs, a lower plate secured to the gin and having upwardly projecting ribs registering with adjacent ribs on the upper plate, the aligned ribs on said plates being spaced from one another adjacent the teeth of the saws to provide a gap which extends beyond the saws, said upper plate having the spaces between the ribs closed by a web except at the ends adjacent the gap, the inner wall of the web between the ribs being concave and merging at one end with the outer face of the upper plate and converging at its opposite end toward the gap, and revolute members positioned in close proximity to the ribs of the upper plate for conducting cotton collected thereon to the gap during the operation of the machine, the spaces between the ribs of the upper section coacting with the web to form recesses for receiving the seed and prevent the latter from being damaged by the revolute member.

9. In a cotton gin of the class described a roll box, gin saws associated with the roll box for conducting the cotton thereto, a huller breast having an upper huller rib rail and a spaced lower huller rib rail, an upper plate connected to the upper rib rail adjacent the saws and provided with depending spaced ribs, a lower plate connected to the lower rib rail and having upwardly extending spaced ribs registering with adjacent ribs on the upper plate, the aligned ribs on said plates being spaced from one another adjacent the peripheries of the saws to provide a gap, the ribs of the upper plate being provided with rounded corners and connected by web portions terminating short of the free ends of the ribs to provide open spaces between the ribs adjacent the gap, a series of seed fingers pivotally mounted in the front of the roll box, said fingers being dis-

posed above and in vertical alignment with adjacent ribs on the upper plate, and a revoluble member having a plurality of opposed and alternately disposed blades positioned in close proximity to but out of engagement with the spaces between the ribs in the upper plate whereby to move cotton collected on the ribs of the upper plate toward the gap and the gin saws.

10. A cotton gin of the class described including gin saws, spaced huller ribs in cooperative relation to the saws, said ribs being interrupted to provide an upper section and a lower section separated by a transversely disposed gap, the ribs of the lower section extending upwardly to the periphery of the saw teeth so that the gap extends outside of the saws to provide a clear space for the cotton to pass through, said upper section having the ribs thereof closed by a web for directing the cotton seed inwardly towards the saws and for preventing the seed from falling through the spaces between the ribs of the upper section, said web terminating short of the lower free ends of the upper ribs to provide through openings between the upper ribs adjacent the gap, and revoluble means disposed relative to the upper section and the gap for imparting a wiping action

to the cotton collected on the upper section to move the same toward the gap and the gin saws.

11. A cotton gin of the class described including gin saws, spaced huller ribs in cooperative relation to the saws, said ribs being interrupted 5 to provide an upper section and a lower section separated by a transversely disposed gap, the ribs of the lower section extending upwardly to the periphery of the saw teeth so that the gap extends outside of the saws to provide a clear space 10 for the cotton to pass through, said upper section including a plate having spaced depending ribs projecting from the underside thereof, the opposite side of the plate having a transverse web overlapping the spaces between the ribs and terminating short of the lower free ends thereof to close the spaces between the upper ribs so as to prevent cotton from looping around the ribs, revoluble means disposed relative to the upper section in the gap for moving the cotton collected on the upper section towards and through the gap so that the cotton is fed by the saws through the gap without looping around the ribs or congesting thereon, and means for adjusting the revoluble member relative to the huller ribs. 15 20 25
